UNITED STATES PATENT OFFICE.

PERRIN L. BERRY, OF WATER VALLEY, MISSISSIPPI.

PERMUTATION LOCK.

Application filed June 30, 1924. Serial No. 723,335.

To all whom it may concern:

Be it known that I, PERRIN L. BERRY, a citizen of the United States, residing at Water Valley, in the county of Yalobusha and State of Mississippi, have invented certain new and useful Improvements in Permutation Locks, of which the following is a specification.

This invention relates to permutation door locks, and has for one of its objects to improve the construction and increase the efficiency and utility of devices of this character.

Another object of the invention is to provide a device of this character including a lock bolt, a latch bolt operative independently of the lock bolt and maintained normally in open position by a gravity operated element, and a system of tumblers adapted to control a bolt releasing and locking device.

With these and other objects in view the invention consists in certain novel features of construction as hereinafter shown and described and then specifically pointed out in the claims, and in the drawings illustrative of the preferred embodiment of the invention.

Figures 1 and 2 are side elevations of the improved lock from the front and rear.

Figure 3 is an elevation of the improved lock with casing face plate removed.

Figure 4 is a transverse section on the line 4—4 of Figure 3 with both the front and rear face plates attached.

Figure 5 is a detail, partly in section, illustrating the operation.

Figures 6, 7 and 8 are detached side views of the tumbler members.

Figure 9 is a side view detached, of the slotted coupling member between the tumblers and the lock bolt.

Figure 10 is a plan view of the lock bolt and the releasing slide.

The improved lock comprises an oblong casing formed with enclosing upper and lower walls 10 and 11, end walls 12 and 13, detachable front face member 14 and detachable rear face member 15.

The interior of the casing is provided with spaced partitions 16 and 17 which unite the ends 14 and 15, thus forming the interior of the casing into three oblong compartments which, for the purpose of this description will be referred to as the upper, the lower, and the intermediate compartments.

Slidably disposed in the lower compartment is a lock bolt comprising a head portion 18, corresponding in thickness to the distance between the face plates 14 and 15, and a shank or stock portion 19, corresponding in thickness to about one half of the distance between the face members, as indicated in Figures 4 and 10.

The head portion 18 of the bolt completely fills the space between the bottom 11 and the partition 17 of the casing, while the shank portion 19 fills about one half of this area, and slidable within the lower compartment between the shank 19 and the side member 15, is an operating block or slide 20 having reversely inclined upper faces 21 and 22.

Slidably disposed in the upper compartment are a plurality of flat plates, three for illustration, and denoted by the characters 23, 24 and 25 and constituting the tumblers of the improved lock.

The tumblers are formed respectively with longitudinal bars 26, 27 and 28, and notches 29, 30 and 31 in their lower edges, the bars and notches not being in alinement or registering when the tumblers are superposed and with their ends coinciding.

The bars 26, 27 and 28 are each provided with a plurality of spaced apertures 32 in one of which pins 33 are set and project through slots 36' in the face member 14 and corresponding slots 36' in the face member 15.

Each of the tumblers is thus provided with an operating pin projecting beyond the outer faces of the face plates so that the tumblers can be independently operated from either side, and by providing a plurality of the apertures in each bar, for the pins 33 the combination can be changed, as required, as hereinafter explained.

The face members 14 and 15 are provided with plates 36 having slots 36' registering with like slots in the plates 14 and 15, the plates 36 being provided with graduations indicated at 38, to denote the required relative positions of the tumblers, as hereinafter explained.

The shank portion 19 of the lock bolt is provided with a transverse recess 39 having its ends at right angles to the longitudinal axis of the bolt, and extending through the slide member 20 is a pin 40, the latter extending through the recess 39 of the bolt 18—19 and likewise through slots 41 in the face members 14 and 15, as indicated in Fig-

ures 1 and 2. By this means the slide member 20 may be operated from either side of the lock within the range of the recess 39. Disposed for movement between guide ribs 5 42 within the intermediate compartment is a slotted coupling member 43, the latter projecting at the ends through guide slots in the partitions 16 and 17. At its upper end the member 43 enters the recesses or seats 10 29, 30 and 31 of the tumblers when the latter are adjusted to locate the seats in transverse alinement.

The shank portion 19 of the lock bolt is provided with seats 44 and 45, so spaced that 15 when the bolt is withdrawn the coupling member 43 will enter the seat 44 and hold the bolt withdrawn, and when the bolt is projected the member 43 will enter the seat 45 and hold the bolt projected.

20 Pivoted at one end at 46 within the intermediate compartment is an L-shaped lever having a short arm 47 and a long arm 48, the latter extending through the slot of the member 43 and provided with a weight 49 25 at its free end.

Slidably disposed in the intermediate compartment and operative through a guide slot in the end member 12 of the casing, is a latch bolt 50, the latter pivoted at 51 at the elbow 30 of the lever 47-48.

Mounted for rotation through the face members 14 and 15 is a knob spindle 52 having an arm 53 extending into a slot or seat 54 in the latch bolt 50.

35 By this arrangement the weight 49 exerts its force to hold the member 43 yieldably in its downward position and the latch bolt 50 yieldably in projected position.

When the latch bolt is to be withdrawn, 40 the spindle 52 is rotated by operating its knob in the usual manner, this movement causing the arm 53 to actuate the bolt to swing the lever 47-48 on its pivot against the resistance of the weight 49, the portion 45 48 of the lever moving upwardly in the slot of the member 43 but without affecting the latter. The latch bolt can thus be actuated regardless of the positions of the tumblers or the lock bolt, while at the same time the 50 weighted lever performs the two fold function of a means for holding the latch bolt yieldably in projected position and also holding the member 43 yieldably in its lower position.

55 The location of the recesses 29, 30 and 31 in the tumblers will vary with each lock and the pins 33 will be set in the perforations in the tumblers to correspond with the tumbler recesses, and by varying the relative location 60 of the pins and recesses a large number of different combinations may be effected, as will be obvious.

To operate the device one of the face plates is removed and the tumblers adjusted to 65 locate the three recesses 29, 30 and 31 in

alinement, or in position to receive the member 43 when elevated. The pins 33 are then located in the apertures opposite certain of the graduations, on the plates, for instance 3, 5 and 6 as shown in Figures 1 and 2. The 70 face plate 14 or 15, as the case may be, is then restored to the casing, and the pins 33 actuated to move the tumblers to the right or left to change the relative location of the recesses in the tumbler, or to break up the 75 alined position.

Then the only way in which the recesses can be set in alined position is to set the pins 33 opposite the selected graduations, for 80 instance 3, 5 and 6, this combination being known only to persons authorized to open the lock, all others will be unable to open the lock.

If the lock bolt 18-19 is in open position as shown in full lines in Figure 3, the member 43 will enter the seat 45, and thus lock the bolt in open position, and if the bolt is in closed position as indicated by dotted lines, the member 43 will enter the seat 44 and lock the bolt in closed position, and the 90 bolt can be released from either open or closed position only by adjusting the tumblers to locate the recesses 29, 30 and 31 in transverse alinement, as above noted.

When the tumblers are adjusted to bring their recesses in transverse alinement by setting the pins 33 opposite the proper graduations, as above noted, then the pin 40 may be moved to the right or left, as the case may be, and cause the inclined face 21 or 22 to elevate the member 43 into the alined recesses 29, 30 and 31 against the resistance of the weight 49, and thus release the lock bolt, and when the pin 40 reaches the end of the recess 39 it will pick up the bolt and move it either into open or closed position, as will be obvious.

The improved device is simple in construction, can be inexpensively manufactured, of any required size, and of any suitable material, and adapted for use wherever a lock of the permutation or combination class is required.

The preferred embodiment of the invention is disclosed in the drawings and set forth in the specification, but it will be understood that modifications within the scope of the claimed invention may be made in the construction without departing from the principle of the invention or sacrificing any of its advantages.

Having thus described the invention what is claimed as new is:—

1. A lock of the class described, comprising an enclosing casing having a plurality of graduations, a plurality of superposed tumbler members within said casing and each provided with a seat in one edge, operating pins extending respectively from said tumblers and co-acting with said gradu-

ations, a lock bolt movable in said casing and having spaced recesses in one part and an elongated cavity in another part, a coupling member between said tumblers and lock bolt 5 and adapted to be alternately engaged with the seats of the tumblers and the recesses of the bolt, a slide within the casing and having reversely inclined edges adapted to engage the coupling member, and an operating 10 pin extending from the slide and through the cavity of the bolt and adapted to engage the ends thereof and move the bolt into projected or withdrawn position.

2. A lock of the class described, comprising 15 an enclosing casing having a plurality of graduations, a plurality of superposed tumbler members within said casing and each provided with a seat in one edge, operating pins extending respectively from said

tumblers and co-acting with said graduations, a lock bolt movable in said casing and having spaced recesses in one part and an elongated cavity in another part, a coupling member longitudinally slotted and movably disposed between said tumblers and lock 25 bolt and adapted to be alternately engaged with the seats of the tumblers and the recesses of the bolt, means for actuating the coupling member, an L-shaped lever member pivoted at one end to the casing and weighted at the other end and passing through the slot of the coupling member, a latch bolt 30 slidable in the casing and pivotally connected to the lever, means for actuating the latch bolt.

In testimony whereof, I affix my signature hereto.

PERRIN L. BERRY.
